TOY KANGAROO FIGURE

Charles B. Root, Morristown, N.J., assignor to Educational Design Associates

Filed Aug. 23, 1972, Ser. No. 283,072

Term of patent 14 years

Int. Cl. D21—01
U.S. Cl. D34—2 RFIG. 1 is a perspective view of the rear, top and right side of a toy kangaroo figure showing my new design.

FIG. 2 is a front elevational view.

FIG. 3 is a left side elevational view.

FIG. 4 is a bottom view.

I claim:

The ornamental design for a toy kangaroo figure, substantially as shown.
